UNITED STATES PATENT OFFICE.

JOHN CONNELL AND VALENTINE DENGLER, OF ROCHESTER, NEW YORK.

SEGMENT-SAW.

SPECIFICATION forming part of Letters Patent No. 279,344, dated June 12, 1883.

Application filed September 16, 1881. (No model.)

To all whom it may concern:

Be it known that we, JOHN CONNELL and VALENTINE DENGLER, residents of the city of Rochester, county of Monroe, and State of New York, have jointly invented certain Improvements in Segment-Saws, of which the following is the specification, reference being had to the annexed drawings, in which—

Figure 1 is a side elevation of our improved segment-saw for resawing-machines. Fig. 2 is a vertical section thereof on the line *y y*, Fig. 1. Fig. 3 is a vertical section, showing the modifications of the construction of the saw. Fig. 4 is a section on the line *x x*, Fig. 1, showing the mode of connecting the segments together by the dovetailed plates. Fig. 5 represents a cross-section in the line *z z*.

Our invention relates to an improved construction of segment-saws for use in resawing-machines; and it consists in attaching the saw-segments to the collar and shaft by means of a stiffening-plate secured to the collar and operating to hold the segments in place and to increase the rigidity of the saw.

Our invention also consists in the mechanical details of the construction, as hereinafter more fully set forth.

Our improved segment-saw for resawing-machines is represented in the accompanying drawings, in which—

D D D are the segments; *N*, the collar; *c*, the shaft, and *P* the stiffening-plate.

Any desired number of segments may be used in the construction of our improved saw, and they are secured together, so as to prevent springing sidewise, by one or more dovetailed plates, *R*, Figs. 1 and 4, placed near the peripheries of the segments.

The collar *N* is placed on the board side of the saw, while the stiffening-plate is on the opposite or log side of the saw, that on which the thickest material passes when the machine is used for slabbing. The collar is provided with a central hub, which is attached to the

saw-shaft *c* in any convenient manner—as, for instance, by means of a nut, *t*, forcing the hub against a shoulder or enlargement, *O*, on the shaft either with a key and slot. The flange of the collar projects outward a suitable distance from the hub, and the segments of which the saw is composed are secured to it by means of a row of screws, *E*,

the heads of which pass freely through holes in the stiffening-plate *P*, so that the latter can be removed without disturbing the screws. 55

The collar and stiffening-plates are secured together through the segments by the screws *a a*, Fig. 1, near their peripheries. The screws of the series *E'* have square-shouldered heads, which pass through the stiffening-plate *P* and 60 bear on the segments only, while the screws *a a* are provided with conical heads fitted into countersunk recesses in the stiffening-plate, and operating, when driven home, to bind the collar and stiffening-plate together near their 65 outer margins and to clamp the segments, which are perforated to receive them, between the collar and the plate. The stiffening-plate is fastened to the collar inside the inner edges of the segments by the row or rows of screws *F'*. 70 It results from this construction that any one of the segments may be removed without taking off the plate *P* by simply removing the screws *E'* and *a a* which pass through it, while the stiffening-plate may be detached by taking out 75 the screws *F'* and *a a*, leaving the screws of the series *E'*, by which the segments are secured to the collar.

The segments are connected to each other near their peripheries by the dovetailed plates 80 *R*, Fig. 1, (shown also on a larger scale in Fig. 4, which represents a portion of the edge of one of the segments with one of the dovetailed plates in section.) Notches are cut in the edges of the segments, the opposite sides of which 85 notches are then beveled down from each side of the segments, and the plates *R*, which are preferably of some ductile metal—such as copper—are fitted to the notches.

In assembling the parts, the plates or keys 90 in their completed form may be inserted between the respective sections until the last one is reached. The plates by which this last section will be held are left open or flat at one end, and after being slipped into position are 95 upset or spread by means of a hammer or punch to fit the adjacent surfaces. When it is required to remove a section from the saw, one of the keys is removed by driving it from its place or cutting away the metal at one end, 100 so as to admit of its being readily forced out of position. The plates *R* bind the segments together, so as to make them as rigid practically as a saw made of one piece of steel,

while a saw made of segments is free from the warping or twisting caused by expansion from heat, which affects saws composed of a single piece only.

- 5 The collar may be made of cast-iron, in which case the hub would be cast with it; but we prefer to make the collar of a plate of steel, in which case the hub may be dispensed with—a mode of construction shown in Fig. 3.
- 10 The stiffening-plate is preferably made of tempered steel ground up true like a saw. This plate may be somewhat thinner than the collar, and it is reduced in thickness toward the periphery to a thin edge. By the use of 15 the stiffening-plate the thickness of the collar may be materially reduced, the two together not being any thicker than the collar itself would be if used alone. We have found by practical experience that saws provided with 20 the stiffening-plate fastened to the collar at or near their peripheries possess many advantages over those heretofore in use, in which the segments have been screwed onto the collar. These advantages are principally the increased stiffness which is secured, and the facility which is afforded for the removal and 25 insertion of any individual saw-segment without the necessity of removing or displacing the others or of removing the stiffening-plate.
- 30 A stiffening-plate may be placed on each side of the saw, as represented in Fig. 3, the collar being provided with a flange or tongue to which the stiffening-plates or one of them are secured.

Inserted teeth, as represented at U, Fig. 1, 35 may be employed in the segments of our improved saw.

We claim—

1. In a segment-saw, the flange N, in combination with the stiffening-plate P, the intermediate saw-segments, D, and the screws E', uniting the segments and the flanges, said screws being passed loosely through the plate P, in the manner described and shown, whereby the removal of the plate and of the saw-sections independently of each other is permitted.

2. In a sectional saw, the combination of a flange, N, shouldered or recessed on its side face, the saw-segments seated in and against the said face, the stiffening-plate P, overlapping the surfaces of the segments and the flange, the screws F', uniting the flange and the plate, and the screws E', uniting the segments and the flange and seated at their heads loosely 55 within the plate.

3. In a sectional saw, the combination of the flange N, the stiffening-plate P, the intermediate saw-segments, D, screws uniting the flange and the plate and the flange and segments, 60 and keys R, uniting the edges of the adjacent segments near the periphery, as described and shown.

JOHN CONNELL.
VALENTINE DENGLER.
